UNITED STATES PATENT OFFICE.

WILLIAM GRUNOW, JR., OF BRIDGEPORT, CONNECTICUT, ASSIGNOR TO
ZALMON GOODSELL, OF SAME PLACE.

SNOW-PLOW, SWEEPER, SCRAPER, AND SPRINKLER FOR CAR-TRACKS.

SPECIFICATION forming part of Letters Patent No. 573,511, dated December 22, 1896.

Application filed October 31, 1895. Serial No. 567,473. (No model.)

To all whom it may concern:

Be it known that I, WILLIAM GRUNOW, Jr., a citizen of the United States, and a resident of Bridgeport, in the county of Fairfield and State of Connecticut, have invented certain new and useful Improvements in Snow-Plows, Sweepers, Scrapers, and Sprinklers for Car-Tracks, of which the following is a specification, reference being had to the accompanying drawings, forming a part thereof, in which similar letters of reference indicate corresponding parts.

My present invention relates to improvements in trucks, comprising a snow-plow, a sweeper, a scraper, and a sprinkler, adapted particularly for car-tracks; and its object is to provide a simple construction and arrangement of parts which can be easily adapted for operation.

My invention consists of the peculiar construction and arrangement of parts and combination of devices hereinafter fully and particularly pointed out and claimed.

In the accompanying drawings, Figure 1 is a side elevation of a truck embodying my improvements. Fig. 2 is a bottom plan view. Fig. 3 is a side elevation showing a snow-plow substituted for the brushes and sprinkling devices. Fig. 4 is a top plan view of the construction shown in Fig. 3. Fig. 5 is a sectional view on the line xx of Fig. 4. Fig. 6 is a bottom plan view of the water-tank and its connections. Fig. 7 is a longitudinal sectional view showing the manner in which the truck may be turned around. Fig. 8 illustrates a side wing adapted to throw the snow away from the tracks. Fig. 9 is a detail view. Fig. 10 is a top plan view of a sweeping device which I employ. Fig. 11 is a side elevation of one brush-wheel and showing in dotted lines how the hood may be adjusted, and Fig. 12 is a transverse sectional view.

In the practice of my invention I employ a truck comprising a platform A, screwed upon the side pieces a , which are supported upon the axles a' of the wheels a^2 . This truck may be of any suitable size and shape and it is provided with a post B, having a socket b, adapted to receive a coupling-link b' , by means of which the truck is connected to a car or other means of locomotion.

On each side of the platform and between the wheels are located the sand-hoppers C, and the valves in the lower parts of the hoppers are operated by the levers c, and this feature, as well as the scrapers D, are supported on arms d, secured to a rock-shaft d' , form no part of the present invention, and I will not therefore describe them more particularly.

A water-tank E is supported in the platform by the posts e, which are provided with reduced ends and inserted in holes in the platform; but I may provide sockets e' on the platform to receive the parts, if desired, as shown in Fig. 9, and secure them therein by means of set-screws. A pipe F leads down from the tank, and it extends forward and is branched to supply two hub-sprinklers f or a curved perforated pipe. (Not shown.) The branches f' are supported from the truck by the arms f^2 . A slide-valve G is arranged below the tank in the said pipe, and it is operated by a lever g and connecting-rod g' . A guard-rail H may be arranged on the truck-platform, and a similar rail h and a platform h' may be provided for the tank.

On the forward axle a' I secure loosely two forwardly-extending supporting-bars I, which carry a shaft i in their forward ends. On the end of this shaft i are brush-wheels i' , and the brushes are prevented from throwing dirt on the sprinkling devices, &c., by means of hoods i^2 , adjustably secured on the shaft i by means of set-screws i^3 . The bars I and the shaft i constitute in themselves a supplemental movable frame which is preferably secured upon the journal-boxes of the forward axle, and this frame secures the brushes and supports the sprinkling devices. In order to raise or lower this supplemental frame, I provide a hand-screw J, operating in a shoulder j on the support j' against a rearward and upward projection j^2 on a supplemental frame. By this means the said frame may be raised by operating the screw to force the said projection downward, and by turning the screw in the opposite direction the frame is lowered. On account of this movement of the supplemental frame the pipe F is preferably of some flexible material.

I secure a pulley-wheel K on the shaft i and

a larger pulley-wheel k on the axle a' , and connect these wheels by a belt k' , which is twisted to cause the brushes to revolve in a reverse direction to that of the wheels a^2 . The 5 pulley-wheel k is made in two parts and clamps on the axle by means of set-screws. This pulley-wheel also has an enlarged hub L, provided with recesses and projections adapted to engage corresponding recesses 10 and projections on a sleeve l , fixed on the axle a' and thrown into and out of contact with said hub by means of a lever l' , operating in a grooved wheel l^2 . It will thus be observed that when the hub and sleeve have been 15 brought into contact to form a clutch, the sleeve being fastened to the axle and the hub L loose thereon, the pulley-wheels k K are thrown into operation and the brushes caused to revolve in a reverse direction to 20 the revolution of the wheels a^2 .

Under the forward end of the truck I arrange a jack-screw M, which is adapted to be operated to raise the truck from the ground and the wheels a^2 from contact with the rails, 25 so that the truck may be easily turned around, and to facilitate this turning of the truck I provide in the rear end thereof two wheels m , supported on pivoted arms m' . Above these arms are adjusting-screws N, which operate in sockets n in the truck and bear against the arms. When these screws are screwed down, the rear end of the truck is raised upon 30 the wheels, and it may be then turned around with the jack-screw for a center. To facilitate this turning of the truck, I may provide the rim of the wheels with holes n' to receive a bar or lever. This operation is clearly indicated in Fig. 7 of the drawings.

It is obvious that the sweeping and springing apparatus, or either of them, may be removed, and they are constructed and arranged with this end in view. When these parts are removed, as, for instance, in the winter season or during a snow-storm, I secure in the forward end of the truck a frame comprising a shaft O, arranged at an angle to the axle a' , and an arm o, supporting the forward end of the shaft. This shaft is adapted to rock in its bearings, and it supports a 40 snow-plow o' , which is made of curved boiler-iron, as shown. A lever P is connected to said rock-shaft, and it may be adjusted in position by means of a pin secured in one of the holes in an upright p . By simply operating this lever the snow-plow can be lowered or raised at will.

In order to throw the snow as far away from the truck as convenient, I provide on each side of the truck a side wing Q, which is pivoted to the truck and is connected by a rod g to a lever g' , which may be adjusted on a bar g^2 . These wings may be thrown out to force the snow away from the sides of the tracks or folded in close to the truck.

65 The operation of my improved machine is obvious from the foregoing description, and I will not enter into a further elaboration there-

of, but I would have it distinctly understood that I reserve all rights and privileges of making any and all changes in form and proportion of parts and details of the construction of my invention as fairly fall within the scope thereof.

I have not considered it necessary to show the truck or car in connection with the sweeping device shown in Figs. 10, 11, and 12, but the operation thereof will be readily understood from the following description.

The brush-frame in said Figs. 10, 11, and 12 comprises two arms A', which are preferably secured at the rear ends thereof on the axle or shaft a' , and one or both of these arms may be provided with an extension a^3 , by means of which the frame can be raised or lowered. These arms are connected by two braces a^4 .

80 A shaft B' is supported in the forward ends of these arms, and it carries the brush-wheels i , of some preferred construction, on its ends. This shaft carries a pulley-wheel b^2 , which is geared with another pulley-wheel (not shown) 90 on the axle, by which means the brush-wheels are driven.

85 The hoods c^4 are preferably made of metal, and they comprise a side C^3 and a curved top piece c^2 , the forward end of the hood being 95 inclined outwardly and away from the truck. Each hood is provided with a short hub D', which fits snugly on a collar d^4 , carried by the arm A', so that said hoods will remain stationary while the shaft and wheels revolve. In 100 order to adjust the hoods at the proper angle to accomplish the best results, I provide a set-screw d^2 , by means of which said hoods are secured in place after they are adjusted.

105 In the practical operation of my improved device the brush-shaft i is driven in the reverse direction to the revolution of the carrying-wheels on the truck. The hoods are properly adjusted so that the dirt will be thrown away from the truck, and then the set-screws are fastened. By the peculiar construction of these hoods it will be observed 110 that the dirt is directed away from the truck and to one side of the wheels or tracks.

115 I am aware that many changes in the form and proportion of parts and details of construction of my invention may be made without departing from the spirit or sacrificing the advantages of the invention, and I therefore reserve the right to make all such changes as 120 fall within the scope of the invention.

Having thus fully described the invention, what I claim, and desire to secure by Letters Patent, is—

125 1. The combination with a truck, of arms pivotedly secured on the rear end thereof and carrying wheels on their free ends, the rim of said wheels being provided with a series of holes, the sockets n of the truck-adjusting screws operating through said sockets and bearing on the pivoted arms to raise the rear end of the truck, and a jack-screw supported under the forward end of the truck and adapted to raise the same, whereby the truck may 130

be turned around with the jack-screw for a center, substantially as shown and described.

2. The combination with a truck, of a water-tank supported thereon, a supplemental frame pivotally secured in the forward end of the truck, sprinkling devices carried by said frame and a flexible pipe connected between the sprinkling devices and the tank, substantially as shown and described.

10 3. The combination with a truck, of a platform, posts fitted in sockets, in said platform, a water-tank supported on the post, a supplemental frame pivotally secured in the forward end of the truck, sprinkling devices carried by said frame, a flexible pipe connection between the sprinkling devices and the tank, a slide-valve beneath the tank, and a lever secured on the tank and adapted to operate the valve, substantially as shown and described.

20 4. The combination with a truck, of a supplemental frame pivotally secured in the forward end of the truck, a transverse shaft in the forward end of the frame, brush-wheels mounted on the ends of said shaft and the hoods secured adjustably on the shaft and over the brush-wheels, substantially as shown and described.

25 5. The combination with a truck, of a supplemental frame, pivotally secured in the forward end thereof, an upward extension on said frame, a hand-screw supported on the truck and operating against said extension to raise or lower the frame, arms carried by 30 the frame and supporting sprinkling devices, a shaft mounted in the frame, brush-wheels on the ends of said shaft, hoods adjustably arranged on the shaft and over the brush-wheels a pulley-wheel on the shaft, a larger 35 pulley-wheel on the forward axle, a belt running over said wheels, an enlarged hub on the

larger pulley-wheel provided with notches and projections and a lever adapted to throw said sleeve and hub into engagement, substantially as shown and described.

45

6. The combination with a reversible and vertically-adjustable truck of the character described, of adjustable attachments secured thereto to clean the tracks, sprinkling devices carried by a supplemental frame mounted on 50 said truck, a water-tank supported thereon and flexible connection between the tank and said sprinkler, all combined and arranged as and for the purpose set forth.

7. The combination of a frame secured to 55 a car-truck and comprising two parallel arms, a shaft supported by said arms, the braces connecting the arms, brush-wheels on the ends of the shaft, and hoods adjustably secured on the shaft and over the brush-wheels, 60 substantially as shown and described.

8. The combination of a frame adapted to be secured to a car-truck and comprising two parallel arms, the braces connecting said arms, a shaft supported by the arms and carrying brush-wheels on their outer ends, collars on said arms, hoods arranged over the wheels and having hubs to fit on said collars, and set-screws to fasten the hoods in place, 65 substantially as shown and described.

9. A hood for a brush-wheel having a straight side, a curved top and an outwardly-turned forward end, substantially as shown and described.

In testimony that I claim the foregoing as 75 my invention I have signed my name, in presence of two witnesses, this 30th day of July, 1895.
